UNITED STATES PATENT OFFICE.

JOHN R. HALDEMAN, OF KANSAS CITY, MISSOURI; HATTIE E. HALDEMAN EXECUTRIX
OF SAID JOHN R. HALDEMAN, DECEASED.

LOOSE-LEAF HOLDER.

1,076,570.

Specification of Letters Patent. Patented Oct. 21, 1913.

Application filed September 30, 1912. Serial No. 723,131.

To all whom it may concern:

Be it known that I, JOHN R. HALDEMAN, a citizen of the United States, residing at Kansas City, in the county of Jackson and 5 State of Missouri, have invented certain new and useful Improvements in Loose-Leaf Holders, of which the following is a specification.

My invention relates to improvements in 10 loose-leaf holders, and my object is to provide a new and simple device of this character, which can be manufactured at small cost and is well adapted to the purpose intended.

15 The invention embodies a novel retaining-strip which covers and protects the bound ends of the leaves, and novel means for securing said retaining-strip in place.

Other features of the invention will here- 20 inafter appear, and in order that said invention may be fully understood, reference will now be made to the accompanying drawings, in which:

Figure 1 is a plan view of my loose-leaf holder in open position. Fig. 2 is 25 an enlarged cross section on line II-II of Fig. 1. Fig. 3 is a detail perspective view of my improved retaining strip and a novel locking member for securing said retaining-strip in position upon the leaves, and Fig. 30 4 is a broken horizontal section on line IV-IV, of Fig. 1, with the book in closed position.

In carrying out the invention, I employ 35 a suitable cover 1, to one side of which a pair of binding posts 2, are rigidly secured, said binding posts having peripheral grooves 3, near their upper terminals.

4 designates the retaining-strip, which is 40 of angle iron form to lend rigidity thereto, and so that its upper portion 5, will rest upon the topmost leaf A, while its vertical portion 6, engages the edges of the bound ends of the leaves, and thus protects and 45 holds the same in alinement. The upper portion 5, of the retaining-strip, is provided near its ends with a pair of key-hole slots 7, so that it may be placed in position on the binding-posts as shown.

50 8 designates a locking member for securing the retaining-strip 4, upon the binding posts 2. Said locking member is of angle iron form to fit the portions 5 and 6, of the retaining-strip 4, and is operably-se-

cured to portion 6, by a pivot 9. The piv- 55 oted side of the locking member 8, is pro- vided at its free end with a detent 10, adapted to take into an indentation 11, in the vertical portion 6, of the retaining strip. The upper portion 12, of the locking mem- 60 ber 8, is provided at its free end with an eye 13, to admit the upper end of one of the binding-posts 2.

In practice the loose-leaves A, are placed upon the binding posts 2, until even with 65 the lower edges of the grooves 3. The retaining-strip 4, is then placed in position over the posts and moved longitudinally to the left, so that the edges of the narrow portions of the key-hole slots 7, are brought 70 into engagement with the sides of the grooves 3, so that the heads 14, of the binding-posts will overlap the retaining-strip, and thus hold the same in position upon the leaves A. The locking member 8, is then 75 lowered over the head of the adjacent binding-post, which is snugly embraced by the edges of eye 13, and thus locks the retaining-strip from longitudinal movement. When the locking member 8, is lowered over 80 the head of the adjacent binding-post de- tent 10, enters the indentation 11, and thus reliably secures said locking member in low- ered position, until released by hand.

Having thus described my invention, 85 what I claim and desire to secure by Letters Patent is:

1. A loose - leaf holder consisting of a cover, binding-posts fixed at one end of said cover and having peripheral grooves near 90 their upper ends, a retaining-strip having key-hole slots a portion of the edges of which are adapted to enter said peripheral grooves, a locking member pivoted to the binding-strip and provided at its free end 95 with an eye adapted to snugly fit one of the binding-posts when said locking member is lowered upon the retaining - strip, and means for securing said locking member in lowered position.

2. A loose - leaf holder consisting of a cover, binding-posts fixed at one end to said cover and having peripheral grooves near 100 their upper ends, a retaining-strip having key-hole slots a portion of the edges of which are adapted to enter said peripheral grooves, a locking member pivoted to the binding-strip and provided at its free end 105

with an eye adapted to snugly fit one of the binding-posts when said locking member is lowered upon the retaining strip, and a detent at the free end of said locking member adapted to enter an indentation in the retaining-strip and secure said locking member in lowered position.

In testimony whereof I affix my signature in the presence of two witnesses.

JOHN R. HALDEMAN.

Witnesses:

F. G. FISCHER,
L. J. FISCHER.
